E. J. FREWEN

WALL

Original Filed Nov. 25, 1922

UNITED STATES PATENT OFFICE.

EDMOND JOSEPH FREWEN, OF LONDON, ENGLAND.

WALL.

Original application filed November 25, 1922, Serial No. 603,336. Divided and this application filed July 27, 1923. Serial No. 654,145.

To all whom it may concern:

Be it known that I, EDMOND JOSEPH FREWEN, a subject of the King of Great Britain, residing formerly at Terminus Chambers, 6 Holborn Viaduct, London, England, now of Lincoln House, 296 High Holborn, London, aforesaid, have invented new and useful Improvements in Walls, of which the following is a specification.

10 This invention relates to walls.

According to this invention a wall is composed of one row of T shaped bricks preferably having shallow stems and cross-pieces, each crosspiece having two cavities, 15 and a row of plates having grooves into which the stems of the bricks enter and interlock.

The accompanying drawings show walls made in accordance with this invention in 20 which Figure 1 is a horizontal section of part of a building having an internal buttress, the walls of the building being composed of one row of T shaped bricks having an external facing of plates and Figure 25 2 is a section of a wall as constructed in accordance with Figure 1, showing spaces left between the bricks for the reception of mortar or cement.

Referring to Figure 1, the walls of the 30 building are formed of T shaped bricks *a* whose cross pieces have cavities *bb* and whose stems *e* are shallow and under-cut at *ff*. The bricks *a* may have projections and slots as shown at *g* or may have slots 35 which form a tube for grouting the cement as shown at *h*. The corners of the building are formed of bricks *j* having three cavities *kkk*, while plates or tiles *l*, preferably of stone or artificial stone, having grooved 40 inner surfaces, form the outside of the wall, the grooves *m* receiving the stems *e* of the bricks *a* and securely locking them together. The internal buttress or chimney flue *n* is constructed of bricks *o* which bricks may 45 be used as cross bonding bricks.

Figure 2 shows the spaces *p* left between the bricks *a* for the reception of mortar or cement.

This application is a division of my application Serial No. 603,336, filed November 25, 1922.

What I claim is:—

1. A wall composed of T shaped bricks, each brick having a shallow stem, a cross-piece and two cavities in the crosspiece, and a row of plates each plate having a groove into which the stems of the bricks enter and interlock.

2. A wall composed of T shaped bricks, each brick having a shallow stem, a cross-piece and a projection at one end of the crosspiece and a slot at the other end of the crosspiece, and a row of plates each plate having a groove into which the stems of the bricks enter and interlock.

3. A wall composed of T shaped bricks, each brick having a stem and a row of plates each plate having a plurality of grooves into which the stems of the bricks enter and interlock.

4. A wall composed of T shaped bricks, each brick having a shallow stem, a cross piece and a projection at one end of the cross piece and a slot at the other end of the cross piece, and a row of solid plates each plate having a plurality of grooves into which the stems of the bricks enter and interlock.

5. A wall composed of bricks, each brick having two cavities separated by a central cross piece and having an elevation on one face, each cavity extending into the elevation, and a row of plates each plate having a groove into which the stems of the bricks enter and interlock.

6. A wall composed of bricks, each brick having two cavities separated by a central cross piece and having an elevation on one face, each cavity extending into the elevation, and a row of solid plates, each plate having a plurality of grooves into which the stems of the bricks enter and interlock.

In testimony that I claim the foregoing as my invention I have signed my name this 27th day of June, 1923.

EDMOND JOSEPH FREWEN.
